CIGARETTE PACKAGE

Charles H. Mackie, Brooklyn, N. Y., assignor of
one-half to Augustus L. Merolle, Brooklyn,
N. Y.

Application February 17, 1932, Serial No. 593,600

1 Claim. (Cl. 206—41)

This invention relates to a cigarette package, being in the nature of an improvement upon the structure shown in my pending application Serial No. 473,906, filed Aug. 8, 1930, which has matured 5 into Patent No. 1,894,221, Jan. 10, 1933.

An object of the present invention is to provide a package having the advantages of the package disclosed in said co-pending application and having the added advantage of providing means 10 to permit vision of a portion of the cigarettes within the package adjacent to the cigarette discharge mechanism.

A further object is to provide improved cigarette discharging mechanism.

Other objects and aims of the invention, more or less specific than those referred to above, will be in part obvious and in part pointed out in the course of the following description of the elements, combinations, arrangements of parts 20 and applications of principles constituting the invention; and the scope of protection contemplated will be indicated in the appended claim.

In the accompanying drawing which is to be taken as a part of this specification, and in 25 which I have shown merely a preferred form of embodiment of the invention:—

Fig. 1 is a perspective view of a cigarette package constructed in accordance with this invention.

Fig. 2 is an enlarged fragmentary horizontal plane view taken substantially upon the plane indicated by line II—II of Fig. 1.

Fig. 3 is a vertical sectional view substantially upon the plane of line III—III of Fig. 2.

Fig. 4 is a transverse sectional view taken substantially upon the plane of line IV—IV of Fig. 3, and

Fig. 5 is a similar transverse sectional view 40 taken substantially upon the plane of line V—V of Fig. 3.

Referring to the drawing for describing in detail the structure as illustrated therein it will be seen that the package is of ordinary rectangular contour of the general proportions as common to ordinary cigarette packages adapted for containing a dozen or more cigarettes. The package is formed of paper or cardboard of appropriate thickness and consists of top and bottom walls 1 and 2, opposite end walls as 3 and 4, and front and rear walls 5 and 6. The paper or cardboard from which these walls are formed may be cut, folded and gummed together in any appropriate manner and it will be understood that a separate 55 cover or wrapper of paper, cellophane or the like,

may be placed about the package to more effectually seal the contents if desired.

In the front wall as 5 there is formed an opening 7 of suitable size to permit lateral discharge of cigarettes from the package. Within this 60 opening is a suitable door having a front wall 8 and an inwardly extending bottom wall 9 and opposite end walls 10—10.

This door is pivotally mounted at its opposite ends as at 11—11 upon the opposite end walls of 65 the package and it is of appropriate size to receive and to support one of the cigarettes as 12, approximately as indicated. When the door is swung from its closed to its open position it displaces the supported cigarette outwardly through 70 the opening 7 so that said cigarette will drop out free of the package, the remaining cigarettes within the package being meanwhile retained by the bottom wall 9 of the door.

The wall 9 constitutes a cigarette supporting 75 ledge for picking up and delivering one cigarette each time the door is swung open.

The means by which to manually operate the door is the same in principle as is shown and fully described in my previous application above mentioned, that is it includes a single pull-thread as L extending between the door and finger flap G at the rear of the package.

When a cigarette is to be removed the operator 80 simply bends the flap G outwardly with his finger, thus drawing upon the thread L and swinging the door open.

As a means of resiliently urging the door always into closed position, the present improvement proposes the use of a single resilient tension 85 member, such for instance as a small strip of rubber as H. This strip is connected by its opposite ends with portions as 13—13 at the rear edge of the bottom wall 9 of the door, said portions 13—13 being spaced apart substantially equi-distant at 90 opposite sides of the thread L, the thread L being approximately mid-way in the length of the package.

The strip H has the intermediate portion of its 95 length positioned within a tunnel 14 provided to receive it lengthwise of the bottom wall of the package between the portions 13—13 of the door, the opposite ends of the tunnel opening upwardly and the adjacent end portions as 15—15 of the strip extending upwardly out of the tunnel and 100 into connection with the portions 13—13.

The portions 13—13 are carried by the rear edge of the bottom wall or ledge portion 9 of the door directly at the upwardly opening ends of the tunnel.

The tension of the strip H is such as to always hold the door closed. When the door is pulled open by the thread L the elasticity of the strip permits the strip to be stretched sufficiently to 5 accommodate full movement of the door.

It is noted that by this arrangement the elastic strip is normally concealed and entirely out of the way. Also that when the strip is tensioned by opening movement of the door the full length 10 of the strip, that is not only the end portions of the strip, is stretched, thus avoiding the imposition of excessive strains upon the strip.

It is also to be noted that whenever the door is swung open the end portions of the strip extending 15 between the door and the tunnel ends constitute two spaced guards or barriers across the opening between the bottom wall 9 of the door and the underlying bottom wall 2 of the package, thereby preventing the possibility of 20 cigarettes at any time being caught beneath the bottom wall 9 and blocking the door as the door swings closed.

These barriers will extend from the rear edge 25 of the wall 9 downwardly and will reach the bottom wall 2 of the package at points from which the rear edge of wall 9 has just left. These barriers thus operate to close off only that portion of the bottom wall 2 of the package which lies directly beneath the wall 9. They at no time objectionably disturb any of the cigarettes within 30 the package, but merely serve to hold the cigarettes against rolling onto the portion of the bottom wall 2 beneath the ledge or wall 9.

The bottom wall 2 of the package is preferably 35 formed on its upper surface with a channel as 16 for receiving the thread L between the door and the finger flap G so that the thread will not rub frictionally against cigarettes within the package.

It is a feature of the present improvement to 40 provide means furnishing visual inspection of the cigarettes at the discharge door 8, and to this end the drawing herewith suggests that some or all of the front wall 5 of the package above the door 8 may be made of transparent material, 45 such as celluloid, cellophane or the like, thus furnishing a window as 17 through which a good view may be had of the cigarette or cigarettes within the package adjacent to the door.

This window is useful in that it enables the 50 operator to actually see into the package par-

ticularly at the time when he is about to operate the door for discharging a cigarette. The window enables him to instinctively note that a cigarette about to be discharged by the door is in its proper position upon the door ready to be discharged. If his glance at the cigarette shows the cigarette to be askew, or otherwise not correctly in discharge position, he will instinctively jiggle the package so as to properly position the cigarette before opening the door. 80 85

Of course the window has the further advantage of permitting the operator always to see about how many cigarettes remain in his package from time to time. 90

As many changes could be made in this construction without departing from the scope of the invention, as defined in the following claim, it is intended that all matter contained in the above description, or shown in the accompanying drawing, shall be interpreted as illustrative only and 95 not in a limiting sense. 95

Having thus described my invention, what I claim as new and desire to secure by Letters Patent is:—

A cigarette package comprising top, bottom, side and end walls, one of the side walls having an opening of a size to permit lateral discharge of a cigarette therethrough, the bottom wall having a tunnel formed therein, a pivotally supported manually swingable discharge door normally closing said opening, said door having an inwardly projecting ledge which when the door stands closed overlies a portion of the bottom wall so as to support a cigarette for discharge when the door is swung open, said tunnel having an opposite end openings facing upwardly through the top surface of said bottom wall directly adjacent to the inner edge of said ledge at points spaced apart in the length of said ledge, and means resiliently urging the door closed including a strip of elastic material extending lengthwise through said tunnel having its opposite end portions extending out of the opposite ends of the tunnel substantially directly upwardly to the inner edge of said ledge and fixed to said inner edge directly adjacent the tunnel ends thereby to constitute when the door is opened barriers closing off only that portion of the bottom wall lying beneath the ledge. 100 105 110 115 120
